UNITED STATES PATENT OFFICE.

GEORGE F. MINNIS, OF CHICAGO, ILLINOIS, ASSIGNOR TO NATIONAL SAFETY WINDOW DEVICE COMPANY, A CORPORATION OF ILLINOIS.

ANCHOR AND CLIP FOR WINDOW-WASHERS' HARNESS.

1,404,993.

Specification of Letters Patent. Patented Jan. 31, 1922.

Application filed December 31, 1919. Serial No. 348,615.

To all whom it may concern:

Be it known that I, GEORGE F. MINNIS, a citizen of the United States, residing at Chicago, in the county of Cook and State of Illinois, have invented certain new and useful Improvements in Anchors and Clips for Window-Washers' Harness, of which the following is a specification.

This invention relates to improvements in anchors and clips for window washers' harness.

One of the objects of the invention is to provide an improved anchor and co-operating clip for attachment thereto.

Another object is to provide a clip and anchor in which the clip must be turned substantially ninety degrees to its operating position in order to attach it to or to remove it from the supporting anchor.

Another object is to provide a strong, durable, one-piece clip, safe and reliable, which cannot be removed from its supporting anchor until the operator using it has relieved the rope attached thereto of his weight.

Another object is to provide a clip that may be readily and conveniently attached to and removed from its supporting anchor, projecting from the face of the wall of the building.

Another object is to provide a one-piece clip; another object is to provide a peculiar form of one head anchor.

Other, further and more specific objects of the invention will become readily apparent to persons skilled in the art from a consideration of the following description when taken in conjunction with the drawings, wherein;

Fig. 1 shows a plan view of the anchor as it is arranged in a brick wall of a building and shows the clip attached thereto, in section.

Fig. 2 is an end elevation of the anchor.

Fig. 3 is a central longitudinal section of the clip, and

Fig. 4 is an inverted plan view of the same.

Fig. 5 is a fragmentary elevation showing the clip in operative position on the anchor.

In all of the views the same reference characters are employed to indicate similar parts.

The anchor consists of a head 5, horizontally elongated, having a neck 6 connecting

the body part of the anchor to the head. A flange 7 for intimate contact with the outer face of the wall, is extended horizontally to provide a relatively large flat surface for contact with the wall. A shank 8 extends, 60 preferably, at an angle, less than ninety degrees from the inner face of the flange 7, to bridge the joint between two horizontally adjacent bricks 9 and 10 shown in broken lines in Fig. 1. The shank 8 is grooved, as 65 at 11, and is provided with connecting ribs 12 or depressions, to provide abutments to interlock with the mortar and render the shank of the anchor more difficult to remove from the wall. A downward or upturned end 13, 70 for contact with the inner surface of a course of brick, serves also to retain the anchor in place. The thickness of the anchor is no greater than the thickness of the mortar 14 between the respective courses of bricks. 75 Any sort of anchor shank for the purpose of holding the head 5 in proper support with the outer surface of the wall of the building will, however, answer the purpose.

The clip 15 consists of a single piece having a rectangular part 16, with an oblong opening 17 therein, through which the head 5 of the anchor is passed. Surrounding the opening 17 is a rib 18 to receive the edges 19 of the head after the clip has been moved 80 substantially ninety degrees from the position necessary for placing it upon the head. The two side members 20, of the clip, are connected together as at 21 and 22 thereby making it a very strong structure. Extending axially from one end of the body of the clip is a ring 23, within which to thread a rope to be connected to the belt of a window washer's harness. A flange 24 is located between the body part of the clip and the underside of the ring to provide an opening 25 for a hook to support the water pail of the window washer. A rib or rabbet 26 may bound one end of the rectangular part of the clip to give greater strength and between 85 90 which the rib or flange 18 the head 5 of the anchor is received.

The rib 18 of the clip near the upper end thereof strengthens the structure, and when the clip is in place, it is in contact with the 105 neck 6 and receives substantially all of the weight suspended on the rope, that is secured in the ring 23.

To place the clip upon the anchor, the operator holds the clip with its longitudinal 110

axis in a substantially horizontal plane and moves it toward the anchor so that the head 5 of the anchor will enter the opening 17 in the clip; he then turns the clip so that its 5 longitudinal axis is in a vertical plane. The flange 19 of the head overlies the ribs 18 of the clip and prevents the latter from leaving the head when it is in a vertical plane.

Having described my invention, what I 10 claim is new and desire to secure by Letters Patent is:—

1. A clip for a window cleaner's harness having a base part with an oblong opening therein; a loop extending laterally and longitudinally beyond the opening, within 15 which to secure a rope; a flange between the loop and base having an opening through which to support a pail and a rib extending around three sides of the oblong opening, 20 located laterally between the base and loop.

2. An anchor having a head, an enlarged

flange having a substantially flat face for contact with a wall of a structure, an intermediate neck smaller than the head and flange and interconnecting the same, and a 25 shank extending at an angle to the flange to lie between adjacent courses of the brick forming the wall and to bridge at least one joint between bricks in the same course.

3. An anchor comprising a flange having 30 a flat rear face for contacting the wall of a building, a shank extending at an angle rearwardly from the flange to lie between adjacent horizontal courses of brick forming the wall and bridge the joint between two 35 adjacent bricks in the same course, and a head secured to the forward face of the flange by a restricted neck.

In testimony whereof I hereunto subscribe my name.

GEORGE F. MINNIS.
